UNITED STATES PATENT OFFICE

126,833

DESIGN FOR A SCOOTER SKI

Ralph R. Hylan, Lexington, Mass.

Application December 19, 1940, Serial No. 97,446

Term of patent 14 years

To all whom it may concern:

Be it known that I, Ralph R. Hylan, a citizen of the United States, residing at Lexington, in the county of Middlesex and Commonwealth of Massachusetts, have invented a certain new, original, and ornamental Design for a Scooter Ski, of which the following is a specification, reference being had to the accompanying drawing, forming a part thereof.

The single figure is a perspective view of the scooter ski showing my new design.

I claim:

The ornamental design for a scooter ski, substantially as shown.

RALPH R. HYLAN.
